(57) **CLAIM**

The ornamental design for a temperature sensor, as shown and described.

DESCRIPTION

FIG. 1 is a perspective view of our new invention;

FIG. 2 is a front view thereof;

FIG. 3 is a rear view thereof;

FIG. 4 is a left view thereof;

FIG. 5 is a right view thereof;

FIG. 6 is a plan view thereof; and,

FIG. 7 is a bottom plan view thereof.

The broken lines in the drawings are used to illustrate unclaimed environmental structure and form no part of the claimed design.
